US0D1012927S

(12) **United States Design Patent** (10) Patent No.: **US D1,012,927 S**
(45) Date of Patent: ** Jan. 30, 2024

(54) **SMARTWATCH**

(71) Applicant: **SHENZHEN DO INTELLIGENT TECHNOLOGY CO., LTD.**, Shenzhen (CN)

(72) Inventors: **Yanxiong Zhu**, Guangdong (CN); **Beijie Hong**, Guangdong (CN)

(73) Assignee: **SHENZHEN DO INTELLIGENT TECHNOLOGY CO., LTD.**, Shenzhen (CN)

(**) Term: **15 Years**

(21) Appl. No.: **35/515,363**

(22) Filed: **Aug. 29, 2022**

(80) **Hague Agreement Data**

Int. Filing Date: **Aug. 29, 2022**

Int. Reg. No.: **DM/223985**

Int. Reg. Date: **Aug. 29, 2022**

Int. Reg. Pub. Date: **Oct. 21, 2022**

(30) **Foreign Application Priority Data**

Jul. 25, 2022 (CN) 202230476924.4
